TEMPORARY DRAINPIPE CLOSURE

Gilbert Steele, New York, N. Y.

Application March 2, 1949, Serial No. 79,121

5 Claims. (Cl. 220—24.5)

1

The present invention relates to a temporary, removable closure for closing the ends of tubes or pipes, particularly for closing the ends of the lead pipes of a drainage system for purposes of testing the system or of temporary use, especially on construction jobs, before the systems are completed or the fixtures connected to the pipes.

It is an object of the present invention to provide a temporary closure of the character described which will make an air-tight and water-tight seal at the end of a flexible pipe to which it may be connected under the normal pressure conditions of testing or use.

It is another object of the present invention to provide a temporary closure for flexible drain pipes of the character described which is easy and simple to attach and which forms a safe and secure seal when it is attached in place.

It is a particular object of the present invention to provide a temporary closure for flexible pipes of the character described which is not only easy and simple to attach in place, but is as easy and simple to remove, in spite of the distortion effects on the end of the tube or pipe resulting from the pressures occasioned by the attachment of the closure and the use of the temporary closed system under pressure.

It is a further object of the present invention to provide a temporary closure of the character described which is of relatively simple construction; which is strong and durable and capable of numerous repeated uses; and which is, for the foregoing reasons, highly economical to produce and to use.

The foregoing and other advantages and superiorities of the temporary closures of the present invention will become more readily apparent to those skilled in the art from the embodiment thereof shown in the accompanying drawing and from the description following. It is to be understood, however, that such embodiment is shown by way of illustration only, to make the principles and practice of the invention more readily comprehensible, and without any intent of limiting the invention to the specific details therein shown.

In the drawings:

Fig. 1 is a blown view of the several parts and elements making up the temporary closure of the present invention; shown in order of assembly and partly broken away and in section to disclose structural details;

Fig. 2 is a fragmentary sectional view, in elevation, of an assembled closure of the present invention, shown secured to the end of a pipe; and

Fig. 3 is a view taken along line 3—3 of Fig. 2.

Referring more specifically to the accompanying drawings, the temporary drain pipe closure of the present invention comprises a cylindrical cap, generally designated as 10, consisting of a

2

top wall, 11, having a central aperture, 12, formed therein and of an annular flange, 13, along the edge of the wall 11, and having a plurality of radially disposed adjusting screws, 14, preferably of the wing type, set thereinto. The cap 10 is preferably of relatively heavy metal and of a size adapted to fit over and exteriorly of the free edges of a flexible drain pipe, 15, of lead or the like.

10 Arranged within the cap 10 is a frusto-conical disk or washer, 16, of substantial thickness which is, however, less than the height of the flange 13, and of a diameter less than that of the cap 10; the washer, 16, being disposed in outwardly tapering position.

Preferably, the washer 16 may be made of a non-metallic rigid substance which is slightly yielding to pressure, such as wood, or the like, and it is, likewise provided with a centrally formed axially disposed aperture, 17.

15 Disposed adjacent the reduced end of the washer 16 is a relatively heavy and rigid metal disk, 18, having a central opening, 19, formed therein and provided with a forked edge, 20, 20 which receives and retains therein a relatively thick ring or tire, 21, of a resilient material, such as rubber or the like. The disk, 18, and the ring, 21, are formed to have a combined diameter equal approximately to the widest diameter of the washer 16, and the tire or ring 21 is of circular cross-section and of a thickness greater than the width of the forked edge 20.

25 A second, flat, rigid metal disk or washer, 23, having a central opening 24, and of a diameter less than the combined disk 18 and ring 21 and greater than that of the disk 18, by itself, is disposed against the disk 18, outwardly of the cap 10, its edges, 25, adapted to rest against the sides of the ring 21.

30 35 A bolt, 26, is passed through the registering openings 12, 17, 19 and 24, respectively, of the cap 10, washer 16, disk 18 and washer 23, which bolt 26 is provided with suitable nuts 27 and 28, respectively, on its outer and inner ends.

40 In operation, the cap 10, washer 16, disk 18 and washer 23 are relatively loosely assembled on the bolt 26, by means of nuts 27 and 28. As thus assembled, the closure is fitted over the edge of the pipe 15, with the flange 13 on the outside 45 thereof and the several washers and disk on the inside thereof. The adjusting screws 14 are then turned to press the edges of the pipe 15 against the side face of the washer 16.

50 After the closure is secured on the pipe 15 in this manner, the upper nut 27 is tightened to press the disk 18 against the bottom face of the washer 16 and the washer 23 against the ring 21; the latter being compressed between such washer 23 and the washer 16, to be outwardly pressed against the inner wall of the pipe 15, to form a liquid-tight and air-tight seal.

It will be readily apparent that by reason of the nature of the material from which the washer 16 is formed, which is somewhat compressible and, when made of wood, affords a degree of frictional contact, the cap 10 will be held securely in place thereon by the pressure of the set screws 14, which press the edge of the pipe 15 against the side face of the washer 16. The security of the cap 10 on the pipe 15 is further enhanced by the air-tight and liquid-tight pressure of the rubber ring 21 against the inside of the pipe 15, to hold the closure in place against the standard pressures encountered during testing or temporary use.

It will be further apparent that despite any distortion of the edge of the pipe 15, resulting from the tightening of screws 14 thereagainst, which, in similar devices heretofore used created great difficulties in removing the closure from the pipe, the temporary closure of the present invention will be easily and readily removed on loosening of screws 14 by reason of the outwardly sloping side face of the washer 16 against which the pipe edge is pressed.

This completes the description of the temporary closure for flexible drain pipes of the present invention. It will be readily apparent that many modifications and variations thereof may be made by any one skilled in the art, in accordance with the principles of the invention hereinabove set forth and without the use of any inventive ingenuity. I desire, therefore, to be protected for any and all such modifications and variations that may be made within the spirit of the present invention and the scope of the claims hereto appended.

What I claim is:

1. A temporary closure of the character described, comprising a cap having a flange adapted to fit over the edges of a pipe, screws adjustably set into the said flange, a frusto-conical, non-metallic washer disposed within said cap in outwardly tapering position, a rigid disk having a circumferentially disposed relatively thick resilient ring mounted thereon disposed adjacent said frusto-conical washer, said disk and ring having a combined diameter slightly less than the diameter of said cap, a rigid washer positioned adjacent the said disk, said rigid washer having a greater diameter than said disk and a lesser diameter than said cap, said cap, said frusto-conical washer, said disk and said rigid washer each having a central axial opening formed therein, a bolt passing through all of said axial openings, said bolt having an adjustable locking nut on its outer end whereby said cap, washers and disk may be compressed toward one another.

2. A temporary closure for flexible pipes comprising a cap having a flange adapted to fit over the edge of a pipe, screws adjustably set into said flange, a wooden, frusto-conical washer disposed within said cap in outwardly tapering position, a rigid disk having a circumferentially disposed resilient ring of greater thickness than said disk mounted thereon, said disk disposed against the outer face of said wooden washer, said disk and ring having a diameter slightly less than the diameter of said cap, a rigid washer of greater diameter than said disk and lesser diameter than said cap disposed against the outer face of said disk, said cap, said wooden washer, said disk and said rigid washer each having a central axial opening formed therethrough, a bolt passed through said openings, said bolt having an adjustable nut at each end thereof whereby said cap,

washers and disk may be compressed toward one another.

3. A temporary closure for flexible pipes comprising a cap having a flange adapted to fit over the edge of a pipe, a plurality of radially positioned adjustable screws set into said flange and adapted to be engaged against the wall of said pipe, a frusto-conical non-metallic washer of a slightly yielding material and of a diameter slightly less than said cap at its narrower end positioned within said cap in outwardly tapering position, a rigid disk having a ring of greater thickness than itself and formed of a resilient material circumferentially disposed thereon, said disk positioned against the outer face of said washer, said disk and ring having a combined diameter less than said cap, a rigid washer of greater diameter than said disk and lesser diameter than said cap disposed against the outer face of said disk, said cap, said wooden washer, said disk and said rigid washer each having a central axial opening formed therethrough, a bolt passed through said openings, said bolt having an adjustable nut at each end thereof whereby said cap, washers and disk may be compressed toward one another.

4. A temporary closure for flexible pipes comprising a cap having a flange adapted to fit over the edge of a pipe, screws adjustably set into said flange and adapted to be engaged against the wall of said pipe a frusto-conical non-metallic washer of a slightly yielding material and of a diameter less than said cap at its narrower end positioned within said cap in outwardly tapering position, a rigid metallic disk having a forked edge positioned against the narrow face of said frusto-conical washer, a resilient ring of greater thickness than said disk disposed within the forked edge of said disk, said disk and ring having a combined diameter less than said cap, a rigid washer of greater diameter than said disk and lesser diameter than said cap disposed against the outer face of said disk, said cap, said wooden washer, said disk and said rigid washer each having a central axial opening formed therethrough, a bolt passed through said openings, said bolt having an adjustable nut at each end thereof whereby said cap, washers and disk may be compressed toward one another.

5. A temporary closure for flexible pipes comprising a cap having a flange adapted to fit over the edge of a pipe, screws adjustably set into said flange and adapted to be engaged against the wall of said pipe a wooden washer of a slightly yielding material and of a diameter less than said cap at its narrower end positioned within said cap in outwardly tapering position, a rigid metallic disk having a forked edge positioned against the narrow face of said wooden washer, a resilient ring of greater thickness than said disk disposed within the forked edge of said disk, said disk and ring having a combined diameter less than said cap, a rigid washer of greater diameter than said disk and lesser diameter than said cap disposed against the outer face of said disk, said cap, said wooden washer, said disk and said rigid washer each having a central axial opening formed therethrough, a bolt passed through said openings, said bolt having an adjustable nut at each end thereof whereby said cap, washers and disk may be compressed toward one another.
